UNITED STATES PATENT OFFICE.

ALMY LE GRAND PEIRCE, OF CINCINNATI, OHIO.

EPHEMEROUS DRINKING-CUP AND ADVERTISING MEDIUM.

SPECIFICATION forming part of Letters Patent No. 496,131, dated April 25, 1893.

Application filed May 21, 1892. Serial No. 433,895. (No model.)

To all whom it may concern:

Be it known that I, ALMY LE GRAND PEIRCE, a citizen of the United States, residing at Cincinnati, in the county of Hamilton and State 5 of Ohio, have invented a certain new and useful Ephemerous Drinking-Cup and Advertising Medium; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 The object of this invention is to provide for public drinking-places, such as are found in hotels, assembly halls, rail-way depots and cars, watering places, fountains, &c., and within convenient reach thereof, drinking cups 20 for each individual frequenter of the liquid dispensary, who after done with it, may throw the same away and thereby avoid the objectionable features of a successive use of one and the same vessel by a great many persons. 25 Such an arrangement as to use requires of course a large quantity of cups or tumblers, and to make the idea feasible, especially as to the matter of expense, I have selected a material and devised a construction which 30 makes the cost of a tumbler only nominal. This cost is further reduced by using the cups as a medium for carrying advertisements, for which use they are especially adapted, owing to the fact, that they pass through the hands 35 of a large multitude of people. The material should be very light, so as to reduce the weight where quantities of them have to be carried, like for instance in railroad cars, and their shape should be so, that large numbers may 40 be closely packed or nested together. A special apparatus is desirable and suitably located, which is provided with a sufficient supply of cups and from which by an easy and convenient manipulation, each user extracts 45 the cups as he needs them. I have devised such an apparatus which I make however the subject of a separate patent for which I filed an application on June 7, 1892, Serial No. 435,864. In the selection of the material, 50 while little weight, combined with a sufficient degree of imperviousness to liquids, are essential features, the possibility of attaching

the advertisements in a convenient and ready manner must also be duly regarded. As to weight, I have found paper the best material, 55 and particularly the sheet-paper, in contradistinction to paper-pulp, or papier-maché, because the former is not only cheaper, but permits also the more ready attachment of the advertising matter, which is printed on 60 the blank-sheet of the shell before the cups are formed. Among the different kinds of sheet-paper, I find the so-called tag-paper the most suited, because it possesses a sufficient degree of imperviousness against liquids, to 65 enable the cups to readily hold their contents for a reasonable time, sufficient for their purpose and prevent them from getting soft before their usefulness has passed.

The construction of this cup is explained in 70 the following specification and pointed out in the claims concluding the same as well as illustrated in the accompanying drawings, in which—

Figure 1, shows in a perspective view the 75 front side of the cup. Fig. 2, shows in a similar view the rear side of the same. Fig. 3, is a view of the blank-sheet of the shell of the cup. Fig. 4, shows in an enlarged view the manner of forming the joint, where the up- 80 right edges of the blank are connected. Fig. 5, is a vertical, central section through the blank after the same has been bent to form the shell. Fig. 6, is a perspective view of the bottom of the cup, detached. Fig. 7, is a vertical, central section through the completed 85 cup and after the bottom, shown in the preceding figure, has been put in position.

The shape of this cup is preferably that of an inverted cone-frustum which shape permits 90 ready and close nesting and packing.

10, is the blank of the shell, cut so as to form the proper shape of the cup, when bent and connected. Before bending and connecting however, the advertising matter is 95 best printed thereon, as well as a notice, containing the necessary information as to the manner in which the cup should be used, respectively disposed of after use. The advertising matter is best printed on a space in- 100 closed by some ornamental figure, like a shield for instance, as shown at 11, which more readily attracts the attention of the user to the printed matter thereon. The edges 12,

and 13, of the shell are brought together, one lapping sufficiently over the other to permit a proper union to be accomplished and which union is completed by means of a suitable 5 glue or cement. The shell appears now as shown in Figs. 2, and 5, and the cup is completed by the attachment of the bottom 14. This latter also forms the means to stiffen the otherwise flimsy structure and aid it in retaining 10 its shape and therefore should be of a construction sufficiently rigid to accomplish such purposes. For this reason I construct the bottom as shown in Fig. 6, that is provided with an integral flange 15, the whole 15 being cut out and formed in one operation by a suitable punch and die. The taper of this flange 15, corresponds with the taper of the shell so as to produce a close contact and joint between the two. This latter is finished by 20 means of glue or cement. To obviate an open space between the flange of the bottom and the shell at a point where this latter's thickness is increased by its over-lapping edges at the joint, as shown at 16, Fig. 4, one of these 25 edges is shaved down as shown at 17, in the same figure. After the bottom is secured in place, the cup is completed by putting the false bottom 18, in its proper position and securing it thereat. Such proper position is 30 against bottom 14 which provides the means to secure it to, through the medium of glue. As the false bottom is also used to carry advertising-matter it forms preferably a part of the blank of the main shell, thereby permitting 35 all the printing to be done in one operation. Such double bottom greatly increases the stiffness of the structure and for the rea-

son that the outer or false bottom is partly connected to the shell, the two bottoms, after glued to each other keep each other in place, especially 40 while the glue is drying during the course of manufacture. The inner one or real bottom 14, is prevented from slipping up, and inwardly by bottom 18, which is connected to the shell and cannot follow and the two bottoms, being glued together, cannot drop out on account of the tapered flange 15 which prevents such, in as much as it can not pass through the narrower end of the cup. 45

Having described my invention, I claim as new—

1. A drinking cup or tumbler constructed entirely of paper, and consisting of the body proper, the real bottom 14, secured to it by flanges 15, and the false bottom 18, secured 55 to the real bottom and thereby preventing the same from slipping inwardly, especially during the course of manufacture, all as substantially shown and described.

2. In a drinking-cup of the kind and for 60 the purposes described, the combination with a tapering body or shell of a bottom 14, having a flange 15, of the same taper as the body or shell and the outer or false bottom 18, connected to the shell, the two bottoms mutually 65 assisting each other in retaining their position, all as substantially shown and described.

In testimony whereof I affix my signature in presence of two witnesses.

ALMY LE GRAND PEIRCE.
